Primary Examiner — Ricky Pham(74) *Attorney, Agent, or Firm* — Panitch Schwarze Belisario & Nadel LLP(57) **CLAIM**

The ornamental design for a webbed saucer chair with central pad, as shown and described.

DESCRIPTION

FIG. 1 is a front perspective view of a webbed saucer chair with central pad in accordance with a first preferred embodiment of my new design;

FIG. 2 is a front elevation view thereof;

FIG. 3 is a left side elevation view thereof, a right side elevation view thereof being a mirror image;

FIG. 4 is a rear elevation view thereof;

FIG. 5 is a top plan view thereof;

FIG. 6 is a bottom plan view thereof;

FIG. 7 is a front perspective view of a webbed saucer chair with central pad in accordance with a second preferred embodiment of my new design;

FIG. 8 is a front elevation view thereof;

FIG. 9 is a left side elevation view thereof, a right side elevation view thereof being a mirror image;

FIG. 10 is a rear elevation view thereof;

FIG. 11 is a top plan view thereof; and,

FIG. 12 is a bottom plan view thereof.

The broken lines in the figures are for the purpose of showing environmental structure and form no part of the claimed design.
